CLAIM

The ornamental design for cosmetics bottle as shown and described.

DESCRIPTION

FIG. 1 is a perspective view of cosmetics bottle according to the claimed design.

FIG. 2 is a front view of the cosmetics bottle.

FIG. 3 is a rear view of the cosmetics bottle.

FIG. 4 is a left side view of the cosmetics bottle.

FIG. 5 is a right side view of the cosmetics bottle.

FIG. 6 is a top view of the cosmetics bottle; and,

FIG. 7 is a bottom view of the cosmetics bottle.

The surface shading in the drawings shows the contours of the cosmetics bottle and does not represent surface ornamentation nor coloration of the cosmetics bottle. Any pattern formed by the surface shading forms no part of the claimed design.
